UNITED STATES PATENT OFFICE.

ISAAC W. P. BUCHANAN, OF LEBANON, TENNESSEE.

SPRAYING DEVICE.

Application filed April 8, 1927. Serial No. 182,196.

This invention relates to a spray device which is especially designed for use in lacquer painting, but which, of course, can be used for other purposes, the general object of the invention being to provide a large compression chamber for receiving air from a pump and having means whereby a wide mouth container can be attached thereto, with an eduction tube and liquid tube associated with the chamber, the liquid tube passing through the eduction tube and the chamber and depending into the container and the eduction tube having an adjustable nozzle or tip thereon.

Another object of the invention is to provide a detachable cap for the chamber, with which is connected the pump and the eduction tube as well as the liquid tube, so that these parts can be detached from the chamber by removing the cap.

Another object of the invention is to make the opening in the compression chamber, through which the liquid tube passes, but slightly larger than the tube so that the contents of the container cannot pass into the chamber through said opening when the parts are in operable position.

Another object of the invention is to provide supporting legs for the chamber which extend below the container and act, with the handle of the pump, to support the device on a surface in upright position to allow any liquid which might get into the compression chamber to drain back into the liquid container.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the device, showing the same resting on a flat surface.

Figure 2 is an enlarged sectional view with parts in elevation, with the major portion of the pump omitted.

Figure 3 is a bottom plan view.

Figure 4 is an enlarged longitudinal sectional view through the eduction tube, the liquid tube and the nozzle.

Figure 5 is a view of a container which may be used with the device.

In these views, 1 indicates a container which forms an enlarged compression chamber and which is provided with a neck 2 which is threaded to receive the threaded part of a cap 3, said cap being provided with a dome 4 which carries a threaded projection on its top to receive an extra tip 5. The dome is provided with a pair of threaded holes therein which are arranged at opposite sides thereof, the rear hole receiving the threaded end of a tube 6 of an air pump 7, the tube being provided with a check valve 8 and the front hole receiving the threaded end of an eduction tube 9.

A liquid tube 10 is bent to provide a horizontal part and a vertical part, the horizontal part passing through the eduction tube 9 and the vertical part extending through the cap and through the chamber and through a hole 11 formed in the bottom of the chamber, the lower end of the vertical part extending a considerable distance below the bottom of the chamber. This tube 10 is firmly held in place by screwing the eduction tube far enough into the dome of the cap to force the bend in the tube 10 against the rear wall of the dome and cap so that the tube is rigidly supported between the end of the tube 9 and the rear wall of the cap, and if desired, the tube 10 can be soldered to the cap. It is further supported against movement by a screen 12 placed in the cap under the dome and having a hole therein through which the tube 10 passes. This screen also acts to prevent flames from passing through the eduction tube and the cap into the chamber, when the device is used as a flame producer. The tube 10 is still further supported, and it is also centered in the eduction tube 9, through means of the depressions 13 made in the outer end of the eduction tube and engaging tube 10.

The outer end of the eduction tube is threaded, as at 14, to receive the nozzle or tip 15 so that said tip can be adjusted on the eduction tube and the tip is locked in adjusted position by means of the lock nut 16 threaded on the eduction tube, a washer 17

being arranged between the tip and lock nut to insure a liquid and air-tight joint. I prefer to recess the lock nut, as shown at 18, to receive a portion of the washer.

6 The outer end of the tube 10 projects beyond the outer end of the eduction tube, and said tube 10 has a flaring or conical mouth 19. This mouth causes the stream to spread out, thereby allowing the air to more readily atomize the liquid, which insures the breaking up of the liquid in minute particles, which results in a perfect spray, free of drops. By adjusting the tip on the eduction tube, the spray can be made fine or coarse, 10 as will be understood, and by turning the tip until its interior wall strikes the mouth of the tube 10, air will be prevented from escaping through the eduction tube so that a solid stream of liquid will pass from the tip. 15 The lock nut insures the tip remaining in the position to which it has been adjusted.

20 A threaded flange 20 depends from the bottom of the chamber 1 and is adapted to receive the threaded neck of a wide mouth container 21 which is to contain the material to be sprayed. As shown, the tube 10 depends into the container so that when air is forced into the chamber by the operation of the pump, some of this air will pass 25 through the opening 11 and place the contents of the container under pressure and thus force said contents through the tube 10. Some of the air from the pump will pass 30 through the eduction tube 9 so that the air and liquid will pass from the tip and thus produce a spray, the density of which is controlled by adjustment of the tip. As before stated, if the tip is adjusted until it rests against the tube 10, a solid stream of 35 liquid will be ejected from the device.

40 As stated above, by making the hole 11 slightly larger than the tube 10, air can pass from the chamber into the container without much danger of the contents of the container getting into the chamber through 45 tilting of the device.

45 By making the container with a wide mouth, lacquer and other thick liquids can be easily placed therein and the container 50 can be easily cleaned. This will permit lacquers of different colors to be used in the device, as the container can be easily cleaned to remove traces of lacquer of one color so that a lacquer of another color can be placed 55 therein.

55 I provide containers of different sizes so that when a small job of painting is to be done, a container of small size can be attached to the device, as shown in Figure 1, but when a larger job is to be done, a container of larger size is attached to the device, as shown in Figure 2. Figure 5 shows the form of container also shown in Figure 2.

65 While the bodies of the containers are of

different sizes, their mouths or necks are of the same size so that they will engage the flange 20, and the containers should be of the same height so that they will not come below the ends of the legs 22 which are pref- 70 erably connected together by a loop 23 which embraces the flange, the legs and loop being formed of spring metal so that the leg forming member will frictionally engage the flange. When the device is at rest, the 75 handle of the pump forms one of the supporting points, as shown in Figure 1, so that but two legs are necessary.

As shown in Figure 1, these legs and the handle support the device in substantially 80 upright position so that substantially all accumulated liquid in the compression chamber will drain back into the liquid container through the opening around the liquid tube in the bottom of the compression chamber 85 if liquid should get into the compression chamber from the liquid in the container through improper handling of the device.

90 In order to prevent the escape of material from the nozzle or tip when ever desired, I provide a lever 24 which is pivoted in the forked end of an upright 25 which is clamped to the eduction tube and has its forward end bent downwardly and provided with a pad 26 so that when the lever is 95 tilted, this pad will cover the hole in the tip and thus prevent the escape of material therefrom. A spring 27 is attached to the lever and to the eduction tube and acts to hold the lever in raised position with the 100 pad out of engagement with the nozzle or tip. The lever is provided with a finger piece 28 so that it can be tilted by the operator whenever he desires to cut off the flow 105 of liquid from the nozzle while the compression chamber still contains air.

110 A depending match holder 29 is carried by the eduction tube for holding a match adjacent the nozzle so that the spray will be ignited by the flame of the match when the device contains an inflammable liquid. In this case, the device is useful for making fires and sterilizing objects, etc.

115 The tip 5 may have a different sized opening from the tip 15 so that the tips can be interchanged whenever desired.

120 Gaskets 30 are placed in the cap and in the flange 20 to form tight joints at these points.

125 As before stated, this device is mainly intended for spraying lacquer paint on objects. With this lacquer paint, it is desirable to have a wide mouth container so that the paint can be easily placed therein and the container cleaned, and as the container is of comparatively small size, it is necessary to have an air chamber to receive the compressed air which is used to force the material from the device in a continuous spray. The compression chamber must be large 130

enough in comparison to the rate of liquid discharge to produce a perfectly continuous spray during the reciprocations of the pump. It is also necessary, in devices of this nature, to have the tube 10 firmly supported and its outer end centered in the eduction tube, and I do this by the means above described. By having the parts of the sprayer carried by the cap, they will be removed when the cap 10 is removed, so that they can be easily cleaned, if necessary.

By providing the container 1 for forming a separate compression chamber, a large air space is provided which is entirely distinct 15 from the container holding the material to be sprayed and, therefore, there is no danger of restricting this compression chamber as there is when the compression chamber is contained in the liquid container, by placing 20 too much liquid in the same. In spite of instructions to the contrary, users of these devices will often place so much material in the container as to seriously interfere with the 25 proper operation of the device. By providing this large compression chamber, the pump can be worked slowly as there will be an ample amount of air in the chamber to operate the device under a slow movement 30 of the pump. This large compression chamber also prevents clogging of the spray parts by the material being sprayed, for if the device is held at such an angle that some of the material will pass into the compression 35 chamber, though very little can pass into this chamber through the opening 11, due to the vacuum in the container 21, this material could not pass into the sprayer head unless the container 1 was filled more than half 40 full while the device was lying on its side and, of course, this would never occur. When the device is placed in an upright position again, what little material had entered the chamber 1 would run back into the 45 container 21.

In small work and in decorative operations, it is of the highest importance that an operator may have the advantage of a small, wide-mouth container of from four to 50 ten ounces. This is true both because of the expensive material used and also because it is desirable to have two or more of these small containers available with different colored lacquers, paints, etc., in them. It is 55 quite a serious matter to be compelled to stain and then clean large containers, when the small ones would answer much better.

Now, the small container cannot be used except in connection with a separate compression chamber of at least ten ounces 60 capacity, provided we expect to get reasonably continuous operation,—which, of course, is necessary for any work that is at all satisfactory.

65 The expense and inconvenience in filling

large containers with small quantities of expensive materials is a very important matter.

Another advantage of this type of sprayer with separate compression and liquid chambers is that a larger mouth can be used for convenience in filling, cleaning, etc.

Since the pressure in ordinary spraying is from ten to twenty pounds to the square inch, the head mechanism of this type of sprayer is too delicate to withstand the strain necessary to force a wide-mouth container against its washer closely enough to stop the escape of air. These parts are necessarily delicate both on account of the 80 nature of their functioning and the expense of their construction. Whereas, in the case of a separate compression chamber and separate liquid chamber, the wide mouth can be forced against this washer by grasping the 85 compression chamber in one hand and the liquid chamber in the other.

It will be understood that the above advantages apply to the device when the same is used with ordinary paint or with any 90 other material.

It will also be understood that the cap can be removed from the expansion chamber and placed on a narrow neck container for use with spray material and the like. When so 95 used, the upper part of the container forms the expansion chamber, for producing a continuous spray, and an expansion chamber, such as indicated at 1, is not necessary.

It is thought from the foregoing description that the advantages and novel features of my invention will be readily apparent.

I desire it to be understood that I may make changes in the construction and in the combination and arrangement of the several 105 parts, provided that such changes fall within the scope of the appended claims.

What I claim is:

1. A spraying device comprising a container forming a compression chamber and 110 having an opening in its bottom, a threaded flange depending from the bottom of the container and surrounding the opening, a container having a threaded neck for engaging the threaded flange, the first container 115 having a threaded neck, a cap having a threaded part for engaging the neck, an air pump connected with the cap and communicating therethrough with the chamber for introducing air into the chamber, an eduction tube carried by the cap, a nozzle adjustable on the outer end of the tube, a liquid tube having a part centrally arranged in the eduction tube and another part extending through the first container and through the 120 opening in the bottom thereof into the second container, the opening being slightly larger than the tube.

2. A spraying device comprising a rigid container forming a compression chamber 125

and having an opening in its bottom, a second container secured to said first container and communicating therewith through said opening, a reduced hollow substantially 5 axial extension on top of the first container and in communication therewith, an air pump connected with the extension and communicating therethrough with the compression chamber for introducing air into 10 the chamber, an eduction tube carried by the extension, a nozzle on the outer end of the tube, a liquid tube extending from said nozzle through said eduction tube in spaced relation to the walls of the bore thereof, 15 thence through the extension, the first container and the opening in the bottom of the first container into the second container, the opening being slightly larger than the tube. 3. A spraying device comprising a rigid 20 container forming a compression chamber and having an opening in its bottom, a second container secured to said first container and communicating therewith through said opening, a reduced hollow substantially 25 axial extension on top of the first container and in communication therewith, an air pump connected with the extension and communicating therethrough with the compression chamber for introducing air into 30 the chamber, an eduction tube carried by the extension, a nozzle on the outer end of the tube, a liquid tube extending from said nozzle through said eduction tube in spaced relation to the walls of the bore thereof, thence

through the extension, the first container 35 and the opening in the bottom of the first container into the second container, the opening being slightly larger than the tube and legs carried by one of the containers and extending below the bottom of the second container and forming with the pump handle a three point support for holding the device substantially in an upright position so that substantially all accumulated liquid in the compression chamber will drain 40 back into the liquid container through the opening around the liquid tube in the bottom of the compression chamber.

4. A spraying device comprising a rigid container forming a compression chamber 50 and having a small opening in its bottom, a second container secured to said first container and having restricted communication therewith through said opening, a reduced hollow substantially axial extension on top 55 of the first container and in communication therewith, an air pump connected with the extension and communicating therethrough with the compression chamber for introducing air into the chamber, an eduction tube 60 carried by the extension, a nozzle on the outer end of the tube, and a liquid delivery tube arranged to establish communication between said nozzle and the interior of said second container near the bottom thereof. 65

In testimony whereof I affix my signature.

ISAAC W. P. BUCHANAN.
